FIG. 1.

FIG. 4.

UNITED STATES PATENT OFFICE

2,222,910

FORMING DEVICE

Millard B. Lucker, St. Joseph, Mich., assignor to
 Auto Specialties Manufacturing Company, St.
 Joseph, Mich., a corporation of Michigan

Application June 13, 1938, Serial No. 213,378

6 Claims. (Cl. 153—48)

The present invention relates to a ram or power unit for use as a repair or forming device and more particularly to a unit adopted for straightening and repairing deformed portions of automotive bodies, frames and the like.

The present invention comprehends the provision of a forming unit wherein force is applied between relatively movable parts through the agency of an actuating cam and a lever. More specifically the present invention comprehends a unit as above comprising a housing or casing having a plunger or relatively movable bar centrally thereof, relative movement of the bar being effected at a mechanical advantage by means of the actuating cam directly operated by a lever, the bar and housing being adapted to receive various suitable accessories for applying the resultant pushing and pulling stresses in a predetermined manner. In devices of this class the stresses are normally applied and created by manual control through the intervening agency of means, such as hydraulic controls, gears and threaded advancing means, with the result that the final degree of movement and the force applied is only indirectly under the control of the operator.

It is, accordingly, an object of the present invention to provide a structure as above wherein the cam is actuated longitudinally of the axis 30 of the bar or plunger while being locked thereto by means of a lever which is manually or otherwise actuated and, as a result, the degree of movement and force applied is directly under the control of the operator and provides for accurate forming of the work.

It is a further object of the present invention to provide a forming unit as above wherein the housing is substantially symmetrically arranged at either end and comprises a bar extending axially therethrough and capable of protruding at either end so that the length of the bar is not limited by the structure of the housing whereby the bar employed may be of any desired length and may cooperate with suitable housing attachments to apply forming stresses at any desired point and through various lengths of travel.

The present invention comprehends further the provision of a forming unit as above wherein the central bar comprises an ordinary length of bar material free from any special configuration and wherein the entire unit comprises a structure wherein there are no hydraulic controls, ratchets, rotatable parts or other elements requiring lubrication.

A yet additional object of the present invention is to provide a new and simplified ram structure, as above, having a housing formed of a single, integral piece of metal and being generally axially symmetrical with attachment means at both ends for securing thereto accessories, such as housing extensions, and for supplying and forming tools so that the said accessories are interchangeably attachable with either end of the housing for increasing the utility 10 thereof.

Another object of the present invention is to provide a forming ram unit, as above, having a housing wherein the opposite attachment means for the accessories comprises sleeve portions on 15 either end of the housing with internal threaded portions or other attachment means surrounding but spaced from the bar, the sleeve portions further including outer attaching surfaces for positioning and securing at either end, accessories 20 formed to engage thereabout.

The present invention yet more specifically comprehends the provision of a power unit having an integral housing substantially fully enclosed and free from apertures tending to weaken 25 the structure except for apertures permitting the passage of the central bar and a control aperture permitting access to the cam operating means.

A further object of the present invention consists in the provision of a housing unit, such as 30 the above, wherein an actuating cam is pivotally or tiltably arranged within the housing and has a projecting portion engaging within an interior recess in the housing formed by configurating the housing outwardly without providing an aperture, as a result of which the housing forms a substantially complete enclosure and is free from structurally weakened portions.

Numerous other objects and advantages will more fully appear during the course and progress 40 of the following specification.

Figure 1 is a sectional view taken through a forming unit constructed in accordance with the present invention.

Figure 2 is a side elevational view of a unit 45 similar to that shown in Figure 1 but having the parts thereof rearranged.

Figures 3 and 4 are side elevational views of the above unit modified by the attachment of further forming accessories.

Figure 5 is a detail sectional view taken on the line 5—5 in Figure 4.

Figure 6 is a sectional view taken on the line 6—6 in Figure 4.

Referring more specifically to the drawing 55

wherein the present invention is disclosed more in detail, Figure 1 shows a preferred structure arranged in accordance with the present invention and comprising a central bar or plunger 10 which, in the embodiment shown, is cylindrical in form but which may comprise a varied cross section, such, for example, as that provided by a hexagonal bar or other polygonal shape. Attention is, moreover, directed to the fact that the bar 10 is devoid of any special configuration and has plain, inwardly formed end portions.

Mounted on the bar 10 is an integral housing 12. It will be noted that the housing 12 is formed of a single, integral piece of metal providing a substantially complete enclosure and having a central portion 14 which is generally cylindrical in configuration. The cylindrical, central body portion 14 is partially divided by a transverse, inwardly extending web 16 providing a partition but which is apertured to permit free passage of the bar 10.

Attention is further directed to the fact that the central body portion 14 is free from apertures except for that indicated by the reference numeral 18 provided at the upper side of the housing, as viewed in Figure 1. This aperture is rectangular and elongated in form and is defined by the parallel, outwardly projecting flanges 20 and the transversely extending end walls or flanges 22 and 24, respectively, which are integrally joined therewith.

The central, cylindrical body portion 14 of the housing at either end tapers conically inwardly toward the bar 10 as at 26 and each conical portion terminates in the cylindrical sleeve portions 28. It is to be noted that at the point of juncture between the tapering conical portion 26 and the sleeve 28, the housing is provided with short, integrally projecting flanges 30 which are apertured to a diameter corresponding to that of the bar 10. In other words, the inwardly extending flanges 30 provide bearing portions in which the bar 10 is slidably mounted and positioned and which prevent lateral tilting between the housing and the bar. More specifically, the housing then is mounted slidably upon the bar 10 for movement relatively with respect to the longitudinal axis thereof.

The actuating means interiorly of the housing 50 comprises an actuating cam 32 disposed in the portion or chamber of the housing existing between the central, inwardly projecting flange or partition 16 and the righthand flange 30, as viewed in Figure 1. The actuating and holding mechanism employed in the present device is substantially identical in character with that shown in my co-pending application, Serial No. 184,174, filed January 10, 1938, as well as other applications.

More particularly the cam 32 is a washer-like element completely encircling the bar 10 and being provided with opposite gripping jaws or portions 34 and 36, which portions, by suitable processing, as set forth in certain of my prior co-pending applications, are offset inwardly toward the central plane of the cam whereby a relatively slight pivotal or tilting movement of the cam will effect a relatively quick gripping or releasing action between the portions 34 and 36 and the surface of the bar 10.

The cam 32 is provided with an outwardly projecting toe or lug 37 on one surface engaging one side of the central flange or partition 16 and forced thereagainst through the agency of a compression spring 38. A projecting portion 40

oppositely disposed from the lug 36 is provided with side surfaces having the form of involute gear teeth, as is clearly shown in Figure 1.

A lever actuator 42 extends through the aperture 18 in the wall of the housing 14 to engage the projecting gear tooth portion of the cam member 32 and has an end configuration as at 44 providing a recess of corresponding involute gear tooth formation for opposite interengagement with the portion 40. The actuating lever member 42 is pivotally mounted in the housing by means of a pivot pin 46 passing through the opposed side walls or flanges 20 and held in position therein by upset portions (not shown).

A stick handle is adapted to be inserted into the end of the lever actuator in known manner and it will be apparent from this disclosure that, upon actuation of the stick handle to rotate the lever actuator 42 about its pivot 46, the cam member 32 will be engaged and moved relatively to the housing. Thus, assuming the lever actuator 42 to be moved in a counter-clockwise direction, the projecting gear tooth portion 40 of the cam 32 will be engaged and moved to the right, as shown in Figure 1, and, since the moving force is applied adjacent the upper side thereof, the whole cam will be tilted to cause the bar engaging edges 34 and 36 to lock with the surface of the bar and move it to the right with respect to the housing. When the lever actuator 30 is returned to the position shown, the cam is returned to its leftmost position through the agency of the lever and the spring 38 without moving the bar to the left.

A holding cam 48 is provided for the purpose of preventing retrograde movement of the bar with respect to the housing and is configurated with gripping or locking portions 50 and 52, configurated substantially identically with those hitherto described. The holding cam is provided with oppositely projecting portions 54 and 56. Attention is particularly directed to the fact that the extension 54 provides a lug engaging in a recess 58 formed by bodily displacing a section 60 of the housing outwardly.

A compression spring 62 seated against the central partition 16 forces the cam at all times in a lefthand direction and against a shoulder 64 provided by the lefthand edge of the recess 58. It will be obvious from this disclosure, therefore, that the spring 62, cooperating with the shoulder 64 of the recess, maintains the cam relatively tilted so that the gripping edges 50 and 52 lock with the bar.

In other words, the recess 58, and particularly the shoulder 64 thereof, provides a positioning means or fulcrum with respect to which the cam is slightly inclined. The bar 10 thus cannot be moved in a lefthand direction with respect to the housing unless the opposite, projecting portion or lug 56 of the cam 48 is moved in a righthand direction about the pivot or fulcrum to release the interlocking edges or gripping portions.

Thus, the holding and actuating means in the housing is adapted to cause controlled relative movement between the bar and the housing under controlled force.

The present invention comprehends the utilization of this force by application to suitable forming and shaping tools or accessories and to this end the cylindrical sleeve portions at either end of the housing are interiorly configurated with screw threads 66. Attention is specifically directed to the fact that the threads 66 and, ac-

cordingly, the inner surfaces of the sleeve-like sections 28 are spaced substantially from the surface of the bar 10 whereby they are adapted to receive and rigidly engage a tubular member, such as that indicated in Figure 1 by the reference numeral 68.

This tubular accessory 68 has a threaded end portion which may be securely interengaged with the threads 66, as shown in Figure 1, and, when 10 in the position shown, provides an extension for the housing while permitting the bar to pass freely centrally thereof. At the other end of the tubular extension 68 is threadedly mounted a forming member 70 comprising a projecting finger 72. A correspondingly shaped forming member 74 having an identical finger 72 is 15 configured with a recess 76 adapted to engage over the cylindrical end of the bar 10.

The device described in detail above may be 20 used by inserting the finger portions 72 between opposed parts of members which it is desired to form by spreading apart. Actuation of the lever actuator 42 in the manner above described will progressively cause the fitting 74 to be moved to 25 the right with respect to the fitting 70 to produce a desired action.

Attention is particularly directed to the fact 30 that the extension member 68 may be readily unscrewed from the housing and, together with the attachment member 70, attached to the opposite end of the housing by threading into the sleeve on the other end thereof. Thus the utility 35 of the device is greatly increased by permitting application to forming operations wherein the parts to be formed are either widely or closely spaced. So also the extension 68 may be of any desired length or form.

Another use of the present preferred power 40 unit is shown in Figure 2 wherein the forming accessory 70 is mounted upon the lefthand end of the housing through the agency of a nipple 78. It is important to note that, not only may the forming portions 72 be given a wide range 45 of operative spacing by use of the present housing, but the assembly may be so arranged as to apply the resultant forces to the unit in a preferred manner. Thus, for example, the attaching means 68, as shown in Figure 1, will normally be under the influence of a tensile stress whereas, 50 using the arrangement shown in Figure 2, the nipple 78 will be under compression with the excessive stresses substantially removed from the threads.

There is shown in Figure 3 a yet further arrangement of the present preferred structure, 55 having the tubular extension member 68 threaded in the upper sleeve 28 with a further rigid extension on the housing provided by the fitting 70 on the lower end thereof. The tubular extension 68 has secured thereon a pedestal fitting 80 adapted to bear against any desired means to be formed. The lower end of the bar 10 is provided 60 with a further pedestal fitting or mounting 82. It will be understood that the device of Figure 3 65 may be used in various obvious relationships for forming and shaping.

The power unit constructed in accordance 70 with the present invention provides for the attachment of fittings adapted to engage about the exterior cylindrical surface of the sleeve portions 28 and these may likewise be so mounted as to cooperate with either end of the housing in the manner above described.

The embodiment shown in Figure 4 comprises 75 a unit of the above type having a yoke-like collar

84 mounted on the upper end thereof through the agency of a central bore 86, Figure 6, of corresponding dimension to the sleeve portion 28 and adapted to fit securely thereabout. Set screw means 88 provides for secure interlocking 5 with the housing.

The yoke member 84 is provided with apertures 90 communicating with relatively narrow slots 92 adapted to receive a chain, such as that indicated by the reference numeral 94. It will 10 be apparent that, if the pedestal portion 82, positioned on the end of the rod 10, is placed flatwise against a member to be formed and the chain 94 looped about a suitable bracing or supporting member, actuation of the power unit will cause 15 the force applying fitting 82 to move downwardly, as viewed in the figure, with respect to the chain. Thus, the member to be formed will be moved with respect to the chain until it receives the desired configuration. 20

It is particularly important to note that, when employing the power unit, as in the immediately aforementioned manner, the parts cannot become disassembled since the forces applied are all in a direction opposite to that required for 25 disassembly. In other words, the force applied to the yoke 84 or the chain 94 tends to draw the yoke against the tapering conical portion of the housing whereby disengagement is impossible. At the same time it should be noted that the yoke 30 84 may be mounted on the lower sleeve of the housing, as viewed in Figure 4, in such situations where this use is desired.

The present invention, therefore, provides a 35 simple and improved forming unit having a housing adapted to be engaged by suitable extensions or accessories upon either end. Moreover, the symmetrical configuration of the attaching end portions of the housing provides for the interchangeable application of the same, equivalent 40 or identical accessories to either end thereof. While there has been disclosed in the above specification accessory attaching means comprising set screws and threaded portions, it will be apparent that any equivalent securing means may 45 be applied.

While the holding and actuating cams or washers 32 and 48, respectively, have been specifically illustrated as integral unitary elements, the present invention is not so limited but comprehends 50 substitution of various equivalents. According to one preferred alternative embodiment, the locking washers or cams may each be of laminated form or, in other words, comprise or consist of a plurality of relatively thin plates which are 55 separable and arranged in superposed relationship. Such a construction is described and claimed more in detail in my co-pending application, Serial No. 195,142, filed March 10, 1938.

The present invention provides a power unit 60 enclosing housing which is extremely strong and serviceable, being free from all unnecessary apertures or weakened portions. Thus the only apertures provided are those to accommodate the bar 10 and the control means, and the holding cam, while being normally fulcrumed with respect to the housing, is nevertheless so arranged that this fulcrum is provided without weakening the housing at this point. 65

Changes may be made in the form, construction 70 and arrangement of the several parts without departing from the spirit or scope of the invention, or sacrificing any of its attendant advantages, the form herein described being a pre- 75

ferred embodiment for the purpose of illustrating the invention.

The invention is hereby claimed as follows:

5. 1. In a device of the class described, a central control bar, a housing mounted on the bar and comprising interiorly thereof a pair of cams, the cams having diametrically opposed portions adapted to frictionally lock with said bar, and means to relatively move at least one of the 10 cams with respect to the housing to shift said bar axially of the housing, said moving means comprising a lever pivoted to the housing and adapted to engage said one cam, the other said cam providing a holding means and having a 15 pair of extensions on opposite sides thereof, said housing being formed outwardly to provide a shoulder on the inner wall surface without providing an aperture in the said wall, one of said holding cam extensions engaging against said 20 shoulder to provide a fulcrum about which the cam is adapted to pivot, and the other of said holding cam extensions serving as a release means for said cam.
2. In a forming unit of the class described, 25 a bar and a housing mounted on the bar for slideable movement with respect thereto, said housing having mounted therein a pair of cams adapted to frictionally engage the bar when moved into canted position within the housing, one of said 30 cams being an operating cam for moving the housing relative to the bar and the other of said cams being a holding cam for holding the housing and bar from movement, a lever pivoted to the housing and engageable with the operating 35 cam for operating it, the holding cam being provided with oppositely extending projections, a fulcrum pivot provided on the housing against which one of said holding cam projections is adapted to engage, an opening formed in the 40 housing through which the other of said holding cam projections is adapted to extend, spring members adapted to engage both of said cams for normally holding them in predetermined position, said housing being arranged axially of the 45 bar and having axial end portions comprising sleeve-like extensions arranged about the bar, said sleeve-like extensions being adapted for securing to forming accessories at either end of the housing.
50. 3. In a forming unit of the class described, a bar and a housing mounted on the bar for slideable movement with respect thereto, said housing having mounted therein a pair of cams adapted to frictionally engage the bar when moved into canted position within the housing, one of said cams being an operating cam for moving the housing relative to the bar and the other of said cams being a holding cam for holding the housing and bar from movement, a lever pivoted to the housing 55 and engageable with the operating cam for operating it, the holding cam being provided with oppositely extending projections, a fulcrum pivot provided on the housing against which one of said holding cam projections is adapted to engage, an opening formed in the housing through which the other of said holding cam projections is adapted to extend, said last named holding cam projection lying in the plane of operation of said lever and adjacent thereto, spring members encircling 60 the bar and adapted to engage both of said cams for normally holding them in predetermined position, said housing being arranged axially of the bar and having axial end portions comprising sleeve-like extensions arranged about the bar, said 65
5. In a forming unit of the class described, a bar member, a housing mounted on the bar member and encircling the bar member, said housing being mounted for relative movement longitudinally of the bar member and having therein at least one cam adapted to frictionally engage the bar when moved into canted position 10 within the housing, said cam being provided with oppositely extending projections, a fulcrum provided on the housing against which one of said cam projections is adapted to engage, the housing being formed with an opening through which the other of said cam projections is adapted to extend, said last named cam projection being an operating projection for the cam, a spring engageable with the cam for normally holding it in canted position in frictional gripping engagement 15 with the bar, the bore of said cam having cut-away sections to decrease the thickness of said cam along the bore portion, and said housing being provided with a sleeve-like extension arranged about the bar and spaced therefrom, said extension being provided with screw threads for attachment to housing extension means. 20
25. 5. In a forming unit of the class described, a bar and a housing mounted on the bar for slideable movement with respect thereto, said housing having mounted therein a pair of cams adapted to frictionally engage the bar when moved into canted position within the housing, one of said cams being a holding cam and the other of said cams being an operating cam, a spring engageable with the holding cam for normally urging it into canted position, a baffle wall within the housing against which the operating cam may be engaged and held in uncanted position, a spring for normally holding the operating cam in engagement 30 with the baffle wall, an operating lever engageable with the operating cam for moving it against the action of its associated spring, said housing being arranged axially of the bar and having at least one end portion comprising a sleeve-like extension 35 arranged about the bar, said sleeve-like extension being provided with securing means adapted for the securing of forming accessories. 40
45. 6. In a forming unit of the class described, a bar and a housing mounted on the bar for slideable movement with respect thereto, said housing having mounted therein at least one cam adapted to embrace and frictionally engage the bar when moved into canted position within the housing, said cam being a holding cam for holding the housing against movement relative to the bar when the cam is in canted position, a spring for normally urging the cam into canted position, and an extension provided on the cam adapted to 50 project radially outwardly from the housing, the housing being formed with an opening and a fulcrum surface adjacent said cam extension adapted to receive an operating bar whereby to permit the bar to be arranged within the opening and 55 in engagement with the fulcrum surface and the cam extension to release the cam against the action of the spring, and said housing being arranged axially of the bar and having at least one end portion comprising a sleeve-like extension arranged about the bar, said sleeve-like extension being provided with attachment means adapted 60 for securing to forming accessories. 65
70. MILLARD B. LUCKER.
